UNITED STATES PATENT OFFICE.

WILLIAM H. HOLDER, OF MILWAUKEE, WISCONSIN, ASSIGNOR TO THE CUTLER-HAMMER MFG. CO., OF MILWAUKEE, WISCONSIN, A CORPORATION OF WISCONSIN.

CIRCUIT CONTROLLER.

Application filed December 6, 1918. Serial No. 265,517.

To all whom it may concern:

Be it known that I, WILLIAM H. HOLDER, a citizen of the United States, residing at Milwaukee, in the county of Milwaukee and

5 State of Wisconsin, have invented new and useful Improvements in Circuit Controllers, of which the following is a full, clear, concise, and exact description, reference being had to the accompanying drawing,

10 forming a part of this specification.

This invention relates to circuit controllers and more particularly to controllers for motor driven devices operating between predetermined limits.

15 Among the objects of the invention is that of providing a controller effective to limit operation of the controlled device to a predetermined range and, also operable at will for starting, stopping and reversing 20 of the controlled device within the range limits thereof.

A further object is to provide a controller of the aforesaid character wherein provision is made to insure against restarting

25 of the controlled device in the same direction following attainment of its limit in that direction and prior to actual movement thereof in the reverse direction.

A still further object is that of providing 30 a controller of the character aforesaid wherein a single switch mechanism is adapted to perform all requisite functions thereof, which mechanism may also be readily adapted without modification of its 35 permanent structure to use in other analogous control systems.

Various other objects and advantages of the invention will hereinafter appear.

The accompanying drawing illustrates an 40 embodiment of the invention particularly applicable to trucks having platforms to be raised and lowered by electric motors and the same will now be described, it being however, understood that the capabilities of the 45 invention are in nowise limited to the use stated, and that the embodiment illustrated is susceptible of various modifications within the scope of the appended claims.

In the drawing,

50 Figure 1 is an elevational view of the controller with certain parts removed and others shown in section;

Fig. 2 is a similar view but taken at a different angle;

Fig. 3 is an elevational view of the switch 55 mechanism;

Fig. 4 is an elevational view of the switch operating mechanism;

Figs. 5 and 6 are detail views of portions 60 of the switch operating mechanism;

Fig. 7 is a diagrammatic view illustrating the use of the controller for starting and limiting a reversible motor; and,

Fig. 8 is a similar view illustrating the applicability of the control switch to systems 65 wherein the motor is non-reversing.

Referring to Fig. 1, the controller comprises a switch including contact members 1 and 2 fixed to a shaft 3, a member 4 mounted on the shaft 3 to slide axially thereof but to rotate therewith, a member 5 rotatably mounted on the shaft 3 and movable either manually or otherwise between an intermediate "off" position and extreme "on" positions, and a releasable 75 connection between the members 4 and 5. Said connection includes pawls 6 and 7 (Figs. 5 and 6) which are carried by the member 5 and arranged to engage the member 4 subject to disengagement therefrom 80 selectively upon movement of said member axially of the shaft 3. The member 4 is so operable by an oscillating shifter 8, similar to that of a friction clutch, which shifter is fixed to a shaft 9 adapted to be coupled 85 to and driven by the mechanism to be controlled.

The member 4, as best illustrated in Figs. 4, 5 and 6, is provided with spaced lugs 10 and 11 to be respectively engaged by the 90 pawls 6 and 7, each of which is provided with a blade-like extremity disposed at right angles to said member. Thus each pawl is adapted to engage its respective lug of the member 4 through a given portion of the 95 range of movement thereof axially of the shaft and so long as both of said pawls engage their respective lugs on the member 4 they afford a connection whereby said member may be rotated in either direction by the 100 member 5 for reverse operations of the switch. On the other hand, the member 4 is movable in one direction to align with a notch 12 in the pawl 7 for release from such pawl and in a reverse direction for release 105 from the pawl 6, but the pawls are staggered to always insure an operative relationship between one of the same and said member,

and project beyond each other sufficiently to preserve such relationship in case of over-travel of the controlled device. Hence in one axial position the member 4 is released 5 from the pawl 7 but subject to movement in a clockwise direction through the medium of pawl 6 while in the opposed position the member 4 is released from the pawl 6 but subject to movement in a counter-clockwise 10 direction through the medium of the pawl 7. As will appear, the member 4 is biased to an intermediate angular position and accordingly assuming the aforesaid range of axial movement of member 4 to correspond 15 to the normal full movement of the driven mechanism, the connection between members 4 and 5 provides for operation of the former by the latter in either direction for corresponding operation of the switch so long as 20 the driven mechanism occupies an intermediate position and for automatic release of the member 4 and consequent return of the switch to its off position when the driven mechanism attains either of its limits. 25 Furthermore when either limit is reached and the member 4 is returned to its intermediate position, the connection insures against return thereof to the position last occupied thereby, while providing for 30 movement of said member, and consequently said switch, in a reverse direction for restarting the controlled mechanism in reverse. When, however, the controlled mechanism is so restarted to move the member 4 a slight 35 distance axially of the shaft 3 said member re-engages the previously disengaged pawl thereby again placing the member 4 and said switch under the control of member 5 for operation in either direction at will.

40 The member 4 is biased to the aforesaid intermediate angular position by a lever 13 held under tension by a spring 14 and provided with a roller 15 to engage the periphery of said member which is provided with 45 cam surfaces 16 and 17 and an intermediate notch 18. The roller rests in the notch in the intermediate angular position of the member 4 and rides onto one or the other of the cams when said member is moved in 50 either direction to bias the same in a reverse direction. The pawls 6 and 7 are secured to the member 5 by bolts 19 and 20 which form pivots therefor and the free ends of said pawls are connected by a tension spring 55 21 to yieldingly retain the same in operative relation with respect to the lugs 10 and 11 of the member 4. In view of the rectilinear movement of the member 4 to disengage and re-engage the pawls it is desirable in order 60 to insure against possible jamming of such parts to cut away said member between the lugs and cam portions thereof as illustrated to clear said pawls. And in the event of either pawl being out of proper alignment 65 with respect to the member 4 when the lat-

ter is moved to re-engage the former the spring 21 permits such pawl to yield and slide over its respective lug for return to operative relation therewith upon relative movement of the members 4 and 5.

70 When the member 5 is to be manually operated it is desirable to provide means for restraining the same in its various positions and to this end there is provided a lever 22 having a roller 23 to engage the periphery of said member which has therein a V-shaped notch 24 to receive said roller in the intermediate angular position of said member and curved notches 25 and 26 to receive said roller in the opposite extreme positions 80 of said member. The spring 14, above mentioned, is also used to hold the lever 22 under tension, to this end being connected at its extremities to the two levers 13 and 22.

85 The switch as illustrated is of the reversing type, the contact elements 1 and 2 thereof being of the construction shown in Figs. 1 and 3 and being arranged to co-operate with stationary contacts also shown in said figures. The contact elements 1 and 2 are 90 of the same construction, each comprising a casting having three contact lugs 30, 31 and 32 and a clamping plate 33 to secure the same to the shaft 3, said shaft being square in cross section and provided with an insulating covering 34. The contacts 30, 31 and 32 are arranged substantially 90° apart and the two elements 1 and 2 are mounted on the shaft in an opposite relation. Further, the contact lugs 31 of the two elements are 100 provided with lateral extensions which are oppositely disposed as best illustrated in Fig. 1. The stationary contacts comprise fingers 35, 36, 37 and 38 arranged in pairs on opposite sides of the shaft 3, the fingers 35 and 37 being disposed in the path of contact lugs 30 and 32 of said element 1 and the fingers 36 and 38 being disposed in the path of the corresponding contact lugs of element 2. Also, both fingers 35 and 105 36 are disposed in the path of the contact lug 31 of element 1 while both of the fingers 37 and 38 are disposed in the path of the corresponding contact lug of element 2. The contact fingers are of a well known yielding type and the pairs thereof are respectively fixed to supports 39 and 40 for insulation of each of said fingers from all of the remaining fingers.

110 Thus when the shaft 3 is rotated clockwise element 1 bridges contact fingers 35 and 37 while element 2 bridges fingers 36 and 38 whereas when the shaft is rotated counter-clockwise element 1 bridges fingers 35 and 36 and element 2 bridges fingers 37 and 38. Accordingly assuming use of the switch for control of a series motor as depicted in Fig. 7, said switch provides for reversal of the direction of flow of current 115 in the armature circuit of said motor. Re- 120

referring to Fig. 7, the motor is shown as provided with an armature A and a series field winding F, said armature being connected between contact fingers 38 and 35 5 while said field is connected between finger 36 to one side of the line, the other side of the line being connected to finger 37. With this arrangement when the movable contact elements, which are shown in plan, 10 are moved to the left, they respectively bridge fingers 37 and 38 and fingers 35 and 36 to complete the motor circuit and to effect flow of current through the armature circuit from left to right. On the other 15 hand, when the contact elements are moved in a reverse direction, elements 1 and 2 bridge finger 35 with finger 37 and finger 36 with finger 38 for completing the motor circuit and effecting a flow of current 20 through the armature from right to left.

While the mechanism above described may be mounted in any preferred manner, the same is shown as enclosed in a casing 42 having a removable cover 43. One end 25 of the shaft 3 has a bearing 44 in one wall of the casing and the other end of said shaft has a bearing in the hub of member 5, while said hub has a bearing 45 in an opposite wall of said casing (Fig. 1). The shaft 9 30 is disposed at right angles to the shaft 3 and as illustrated in Fig. 4 has bearings 46 and 47 in opposite walls of the casing. The levers 13 and 22 are pivotally connected by pins 48 and 49 respectively to lugs 50 35 and 51 provided on the inside of opposite walls of the casing above the bearings of the shaft 9 and the supports 39 and 40 of the contact fingers are secured by bolts 52 to a bracket 53 projecting inwardly from 40 the front wall of the casing. The cover 43 comprises a sheet metal plate having struck in lugs 54 and 55 (Fig. 3) to snap into recesses provided in opposite walls of the casing.

Referring to Fig. 8, the same illustrates diagrammatically a circuit arrangement whereby the aforescribed switch is adapted to control the continuity of circuit of a non-reversible motor having a power connection with the driven device of such character as to provide for operation of the latter in opposite directions.

From inspection of this figure it is obvious that the contact arrangement is identical with that of Fig. 7, whereby with the connections illustrated, the switch is operable as aforescribed to provide automatic stopping of the motor and the controlled device upon operation thereof to the limit 50 of movement of the latter in either direction, whereas following such automatic stopping, the motor may be restarted only upon movement of the switch to its reverse position, while between limits the switch is manually operable both for starting and stop-

ping as in the arrangement aforescribed.

While the constructions aforescribed contemplate the direct control of the motor circuit, it is obvious that suitable relays may be interposed in cases where remote control 70 is desired or where the value of the current to be handled renders such an arrangement necessary or desirable.

What I claim as new and desire to secure by Letters Patent is:

1. In a controller for a motor driven device, the combination with relatively stationary contacts, of a co-operating contacting element movable in opposite directions from an intermediate position for starting 80 the controlled device in opposite directions selectively and actuating means for said contacting element including variable connections controllable for limiting the actuating power of said former means to unidirectional actuation of said contacting element. 85

2. In a controller for a motor driven device, the combination with relatively stationary contacts, of a co-operating contacting element movable in opposite directions 90 from an intermediate off position for starting the controlled device in opposite directions selectively and actuating means for said contacting element including a releasable connection, and means to act upon said 95 connection for rendering said former means temporarily ineffective for actuating said contacting element in one direction.

3. In a controller for a motor driven device, the combination with relatively stationary contacts, of a contacting element biased to an intermediate off position with respect thereto and movable in either direction from such position to engage certain of said contacts for starting the controlled device in opposite directions selectively and actuating means for so moving said contacting element including a connection releasable to prevent movement of said element by said actuating means in one direction from said position. 110

4. In a controller for a motor driven device, the combination with relatively stationary contacts, of a contacting element movable in opposite directions from an intermediate off position to engage certain of said contacts, and actuating means effective within a predetermined range of movement of the controlled device for moving said contacting element in either direction from such intermediate position for starting said device in either direction subject to stopping thereof at will, said actuating means including means subject to release upon movement of the controlled device beyond such range of movement for rendering said actuating means temporarily ineffective to actuate said contacting element in one direction only. 115

5. In a controller for a motor driven de- 130

- vice, the combination with relatively stationary contacts, of a contacting element biased to an intermediate off position relative thereto and movable in either direction 5 from such position to engage certain of said contacts, and actuating means effective within a predetermined range of movement of the controlled device for moving said contacting element in either direction from such 10 intermediate position for starting said device in either direction subject to arrest thereof at will by return of said element, said actuating means including means operable upon movement of the controlled device 15 vice in either direction beyond such range of movement to release said contacting element from said actuating means for return of the former to off position under its bias.
6. In a controller for a motor driven device, the combination with relatively stationary contacts, of a contacting element biased to an intermediate off position relative thereto and movable in either direction from such position to engage certain of said contacts, 20 and actuating means effective within a predetermined range of movement of the controlled device for moving said contacting element in either direction from such intermediate position for starting said device 25 vice in either direction subject to arrest thereof at will by return of said element, said actuating means including means operable upon movement of the controlled device in either direction beyond such range 30 of movement to release said contacting element from said actuating means for return of the former to off position under its bias and to render the latter temporarily ineffective to return the former to the position last 35 occupied thereby.
7. In a controller for a motor driven device, the combination with relatively stationary contacts, of a contacting element biased to an intermediate off position relative thereto and movable in either direction 40 from such position to engage certain of said contacts, an actuating member having an operative connection with said contacting element for moving the same in either direction from such intermediate position for starting said controlled device in either direction selectively, and means to act upon said connection following operation of the controlled device to a predetermined limit 45 to release said contacting element from said actuating member for return of the former to off position under its bias while rendering the latter ineffective for moving the former to the position last occupied thereby pending 50 reverse operation of the controlled device.
8. In a controller for a motor driven device, the combination with relatively stationary contacts, of an oscillatable contacting element adapted to engage the same selectively for starting the controlled device 55 in opposite directions, a relatively oscillatable actuating member having a releasable connection with said contacting element for moving the latter in either direction during operation of the controlled device between 70 predetermined limits and means effective upon movement of the controlled device beyond either of said limits to release said connection and render said actuating device temporarily ineffective for actuating said 75 element in one direction only.
9. In a controller for a motor driven device, the combination with relatively stationary contacts, of a co-operating contacting element and an actuating member therefor, said element and said member having a releasable connection therebetween for causing the same to move in unison in either direction from an intermediate position for starting of the controlled device in opposite directions selectively, and means for effecting release of said connection and temporarily limiting the actuating power of said member to unidirectional actuation of said element pending a given subsequent 80 operation of the controlled device.
10. In a controller for a motor driven device, the combination with relatively stationary contacts, of a contacting member movable in opposite directions to engage the same selectively for starting the controlled device in opposite directions, an actuating member for said contacting member movable in opposite directions, said members having a releasable connection therebetween including means operable in unison with the driven device to temporarily limit the former member to unidirectional operation by the latter member.
11. In a controller for a motor driven device, the combination with a reversely movable contacting member, of a similarly movable actuating member therefor and a releasable connection therebetween including a ratchet member and a pair of opposed pawls 95 normally co-operating therewith to provide for joint movement of said reversely movable members in either direction, said ratchet member being subject to operation in unison with the driven device to selectively disengage said pawls at given limits.
12. In a controller for a motor driven device, the combination with a reversely movable contacting member, of a similarly movable actuating member therefor and a releasable connection therebetween including a ratchet member and a pair of opposed pawls biased to engage the same simultaneously to provide for joint movement of said reversely movable members in either 100 direction, said ratchet member being movable to disengage said pawls selectively.
13. In a controller for a motor driven device, the combination with a reversely movable contacting member, of a similarly 105

movable actuating member therefor and a releasable connection therebetween including a ratchet member and a pair of opposed pawls each adapted to provide for moving
5 said ratchet member in one direction, said pawls normally co-operating to provide for movement of said ratchet member in either direction, said ratchet member being movable in opposite directions to disengage said
10 pawls selectively for limiting such drive to unidirectional operation.
14. The combination with a member to be actuated in opposite directions, of a similarly movable actuating member therefor and an operative connection between said members including a ratchet member adapted to drive said actuated member, a pair of opposed pawls movable with said actuating member and each adapted to move
15 said ratchet member in one direction and means biasing said pawls to engage said ratchet member simultaneously to provide for driving of said actuated member in either direction, said ratchet member being
20 movable independently of said actuated member in opposite directions to disengage said pawls selectively for interrupting such drive in either direction selectively.
25

15. In a controller for a motor driven device, the combination with relatively stationary contacts, of an oscillatable contacting member biased to an intermediate off position relative thereto, and movable from such position for engaging said contacts selectively to provide for operation of the controlled device in opposite directions, an oscillatable actuating member having a releasable connection with said contacting member, said connection including a ratchet member and a pair of opposed pawls biased to engage the same simultaneously to provide for all positions of the controlled device within a given range of operation for moving and holding of said contacting member in either direction by said actuating member at will, and means operable by the controlled device upon movement thereof in either direction beyond such range of operation to move said ratchet member for disengaging one of said pawls to permit return of said contacting member to off position under its bias.
